Inventor

UNITED STATES PATENT OFFICE.

JAMES H. DUMONT, OF KINGSTON, NEW YORK.

GAME-BOARD.

SPECIFICATION forming part of Letters Patent No. 406,342, dated July 2, 1889.

Application filed March 7, 1889. Serial No. 302,266. (No model.)

To all whom it may concern:

Be it known that I, JAMES H. DUMONT, a citizen of the United States of America, residing at Kingston, in the county of Ulster and State of New York, have invented certain new and useful Improvements in Game-Boards; and I do hereby declare the following to be a full, clear, and exact description of the invention, such as will enable others skilled in the art to which it

appertains to make and use the same, reference being had to the accompanying drawings, and to letters or figures of reference marked thereon, which form a part of this specification.

My invention relates to certain new and useful improvements in game-boards, the object of my invention being to provide a game-board which can be folded or set up in a parlor or lawn, said board being adapted to be used in connection with an elastic or non-elastic ball or bag; and my invention consists in the special construction and combination of the parts, as will be hereinafter fully set forth, and specifically pointed out in the claims.

In the accompanying drawings, Figure 1 is a perspective view of a game-board constructed in accordance with my invention, showing the same in position to be played upon. Fig. 2 is a sectional view showing the board folded for storage.

My improved game-board consists of two sections A and B, which are hinged together so that one section will be maintained in a vertical position while the other section is inclined therefrom. The vertical section is provided with legs b b, and above the legs and hinges with baskets c c, which are preferably composed of wire, and also with a bracket d. The section B is also provided near its upper end with an outwardly-projecting screen or shield e, above which an opening is formed in the board.

The section A, which is hinged to the section B, is provided with a plain upper surface having an opening a, and the upper surface thereof is divided into different sections, which may be suitably colored, if desired. To the free end of the board A is secured a strip for re-enforcing the same and protecting the lower edge, while the opposite end is provided with a cross-batten, as shown in Fig. 2. Below this cross-batten are attached hooks f, which en-

gage with the eyes f' for maintaining the parts in proper position.

The wire baskets c c are secured on each side of the center of the board, as shown, and the bracket d is preferably made of rigid material and secured centrally to the board under the opening therein and at a distance below the shield e. The upper surface of this bracket is provided with projecting pins d'.

Above the brackets of the vertical board B are placed arbitrary numbers, preferably the denomination shown. The openings in the vertical and horizontal boards are also provided with arbitrary numbers, as well as the divisions in the board A.

In connection with this game-board bags filled with suitable material, as sand or beans, are used, and it is the object of the players to secure by throwing the bags at the board the highest number of points possible. The inclined screen e extends sufficiently forward to direct the bag beyond the bracket d, and also beyond the opening a in the inclined board.

In playing the game the parties participating stand a suitable distance from the board and throw the bags at the same. A bag thrown upon the first section of the inclined board may count ten; upon the second section, fifteen; upon the third section, twenty, and should the bag pass through the openings in the inclined and vertical boards it will count twenty-five and fifty, respectively. Other points may be made, as indicated by the figures, by landing the bag upon any of the brackets. Should the bag either land on the floor or miss the board entirely, a deduction is made of a suitable number of points.

I claim—

1. The combination, in a game-board, of the sections A and B, hinged to each other, one of said sections being adapted to be maintained in a vertical position when the other section is inclined, brackets c c and d, secured to the vertical board, and an inclined screen e, secured above the central bracket and beneath an opening in the board, substantially as shown.

2. The combination, in a game-board, of the sections A and B, suitably connected to each other, so that one section may be maintained in a vertical position while the other is inclined, the vertical section being provided with brackets c c and d, a screen e, and an

opening above said screen, the section A having its surface divided into sections, the section near the vertical board having an opening *a*, the sections, openings, and brackets 5 being provided with numbers or marks indicative of value, substantially as shown, and for the purpose set forth.

In testimony whereof I affix my signature in presence of two witnesses.

JAMES H. DUMONT.
